UNITED STATES PATENT OFFICE

HARRY E. PAGET, OF CHICAGO, ILLINOIS

WATER HEATER

Application filed December 29, 1928. Serial No. 329,281.

This invention relates to water heaters, and more particularly to that type of heater wherein the water to be heated is passed through coils which are located in a casing or chamber, said coils being surrounded by a body of hot water or steam. In most cases, according to the present day practice, it is customary to connect these heaters with an ordinary steam boiler or hot water boiler of a regular heating plant, by which arrangement an economical heating of the water for domestic and other purposes is accomplished. However, considerable difficulty has been experienced in many cases in dismantling the heater for the purpose of cleaning the interior parts thereof or for making repairs, and, further, these structures are of such character that they are not easily assembled in the first place.

The present invention has for its principal object to produce a simple and inexpensive yet highly efficient and practical structure, which may be assembled and dismantled with ease and facility.

Other objects and advantages to be attained will more fully appear in the following description.

The invention consists in the novel features of construction and in the parts and combinations and arrangement of parts herein-after described and pointed out with particularity in the appended claims.

In the accompanying drawings forming part of this specification,

Figure 1 is a view illustrating a practical installation of a heater according to the present invention;

Figure 2 is a top plan view of the heater;

Figure 3 is a vertical section through the heater, taken on or about the line 3-3 of Figure 2;

Figure 4 is a transverse section taken on or about the line 4-4 of Figure 3; and

Figure 5 is a fragmentary vertical section of the upper portion of a modification of the structure.

Referring now to the drawings, the numeral 10 designates, generally, the water heater of the present invention, which latter is connected to a boiler 11 of an ordinary hot water

or steam heating plant. The connection between the heater 10 and boiler 11 is effected through the pipes 12 and 13, both of which connections are, obviously, below the normal water level in the boiler 11, so as to insure a circulation of hot water through the chamber in the heater 10 as will be later more fully described. The heater 10, as shown, is connected to an ordinary hot water storage tank 14 by the pipes 15 and 16, through which connections the water in the tank 14 is circulated through the coils of the heater 10 so as to be heated thereby, as will be presently set forth.

The heater of the present invention comprises a casing or shell 17, preferably of cylindrical form, and having a closed end 18, from which latter extends a nipple 19 having an axial bore 20 therein. The opposite end of the casing 17 is provided with a removable end closure or head 21, said end closure or head having an annular collar or flange 22 which fits just inside the end of the casing 17. Surrounding the collar or flange 22 is a gasket 23 for making a leak-tight joint between the end of the casing 17 and the end closure or head 21 when the marginal series of bolts 24 are tightened.

At the center of the end closure or head 21 is a threaded nipple extension 25 having a bore 26 which communicates with the passageway 27 extending radially of the head 21 and terminating with a port 28, which latter registers with a port 29 in a lateral lug 30 on the casing 17, and thereby establishes communication with the pipe connection 15 to the storage tank 14 as first herein described.

Within the casing 17 is a coil 31 preferably of copper tubing. To one end of this coil is attached a special fitting or terminal element 32, the latter having an elbow portion 32' into which the end of the coil is fitted and secured as by soldering or welding to afford a strong and leak-tight joint. The element 32 has an axial angular extension 33 at the end of which is a collar 34 which is detachably secured to the nipple extension 25 of the head 21 by a coupling nut 35, a suitable gasket or packing washer 36 being interposed between the adjacent end portions of the nipple 25.

and extension 33 of the fixture 32. At the opposite end of the coil 31 is a fixture 37 which is similar to the fixture 32 except that it has a nipple extension 38 which extends 5 through the bore 20 of the nipple extension 19 of the end portion 18 of the casing 17, said nipple extension 38 being screw threaded at its outer end portion to receive thereon the lock nut 39, which latter impinges the 10 end of the nipple 19 to secure the lower end of the coil with a leak-tight connection, and there being preferably provided a washer or gasket 40 between the nut and nipple. The nipple extension 38 of the fixture 37 is provided with a port 41 to register with an opening 42 in the nipple extension 19, in which opening 42 is inserted the end of the pipe connection 16.

The peculiar end fittings 32 and 37 are 20 essential and important features of the present invention, in that they serve to center the coil within the casing 17 and, further, these fittings make it possible to utilize standard coils of a given diameter but of different 25 lengths. In this way the coils may be obtained in long lengths and the particular coil to fit a heater casing 17 of a certain predetermined size may be cut therefrom, and the fittings 32 and 37 attached to the respective 30 ends thereof; and the portions 33 and 38, respectively, of the fittings are always in axial alignment.

In assembling the heater the fitting 32 of the coil 31 is first attached to the nipple portion 25 of the end closure or head 21. It is then an easy matter to insert the coil 31 into the open end of the casing 17 and project the nipple portion 38 at the opposite end of the coil 31 through the bore 20 in the nipple 40 extension 19 of the closed end portion 18 of said casing. The head 21 is then adjusted to the open end portion of the casing 17, the gasket 23, of course, having first been placed in position on the head 21, the collar or flange 45 22 on the inner side of said head holding said gasket in place and also facilitating the locating of the head on the casing as said collar or flange fits rather snugly within the casing. The head is releasably secured in place by 50 tightening the nuts on the bolts 24, the gasket 23 making the jointure between the head and casing leak-tight and the gasket 36 likewise sealing the jointure between the head and the fitting 32 of the coil 31. The lock nut 39 is 55 then tightened against the nipple portion 19 of the closed end 18 of the casing 17 and the washer 40 which is interposed between said nut 39 and portion 19 and another washer 43 interposed between the inner face of 60 the closed end portion 28 of the casing and the collar 44 on the fitting 37 making this connection leak-tight. Each of the jointures just above described is easily accomplished without any interference from the others, 65 each one being absolutely independent of the

other and so permitted because there is a certain amount of give to the coil 31 in a longitudinal direction. When it is desired to take the heater apart, the nut 39 is detached from the nipple extension 38 of the fitting 37 and the bolts 24 are removed, whereupon the end closure or head 21 with the attached coil 31 may be readily withdrawn from the casing 17.

In some cases where it may not be desirable or practical to disconnect the fitting 37 from the closed end of the casing 17, the structure may be modified as illustrated in Figure 5 of the drawings, in which modification the end closure or head 21 may be disconnected from the fitting by which it is coupled to the coil 31. In this modification, a fitting substantially the same as the fitting 37 is substituted in place of the aforementioned fitting 32. That is to say, the fitting designated generally by the numeral 37 has a nipple extension 45 which is projected through an opening in a boss 46 on the end closure or head 21 and on the threaded outer end portion of said nipple extension 45 is placed cap nut 47 between which latter and said boss 46 is interposed a gasket or washer 48, said gasket 48 and another gasket 49 interposed between the nipple extension 45 and the collar 50 on said fitting 37 making the jointures leak-tight. Said nipple extension 45 is provided with a port 51 to register with the passageway 27 in said end closure or head 21. In other respects the structure is identical with that first herein described.

In assembling the heater constructed according to the above modification, the coil may be first placed in the casing 17 and secured to the closed end portion 18. The end closure or head 21 may be then secured in place on the casing and the cap nut 47 finally applied to the nipple extension 45 of the coupling fixture 37.

In some cases the nut 39 may be closed by a suitable plug, and in other cases a cap nut similar to nut 47 may be substituted for said nut 39. However, it is preferable to attach a short pipe or nipple 52 to said nut 39 and provide on said member 52 a drain cock 53. By the latter arrangement the coil 31 is easily flushed, when necessary, by simply opening the drain cock. In localities where the water contains lime in quantities, whereby the outer surface of the coil becomes coated, it is but a simple matter to remove the coil from the casing 17 as hereinbefore pointed out.

Obviously, the heater may be further modified in its structural details without departing from the spirit and scope of the invention as defined in the appended claims. The invention, therefore, is not limited to the specific construction and arrangement shown in the accompanying drawings.

Having thus described my invention, what

I claim as new and desire to secure by Letters Patent is:

1. In a water heater of the character described, a longitudinally elongated casing having an integral end wall, and having provision near its opposite ends for pipe connections, a removable head for closing the end of said casing opposite to its integral end wall, said integral end wall of the casing having an external axial nipple extension, said nipple extension having a lateral opening for a pipe connection, said removable head having an internal axial nipple extension and a lateral passageway communicable with said nipple extension and a pipe connection provided therefor at the adjacent end of said casing, a tubular coil extending longitudinally within said casing, said coil having an axial nipple extension at one end fitted within the nipple extension of the integral end wall of said casing and having a lateral opening communicable with said lateral opening of said last mentioned nipple extension, means for detachably securing said axial extension of said coil to said integral end wall of the casing, said coil having an axial extension at its opposite end, and means for detachably connecting said last mentioned axial end extension to said nipple extension of said removable head. 70
  2. In a water heater of the character described, a vertically disposed longitudinally elongated casing having an integral bottom end wall, a removable head for the upper end of said casing, said bottom end wall having an external axial nipple extension provided with a lateral opening for a pipe connection, said removable head having an internal axial nipple extension and a lateral passageway providing communication between said nipple extension thereof and a lateral pipe connection at the adjacent end of said casing, a tubular coil in said casing having axial end extensions, and means for detachably connecting the axial end extensions of said coil respectively to said nipple extensions of said end wall and said removable head. 80
  3. In a device for effecting temperatures, a casing having provision for pipe connections, a removable head, an external extension in combination with said casing, said extension having a lateral opening for a pipe connection, an internal extension on said removable head having a passageway communicating said extension with a pipe connection, a coil within said casing having an extension at one end to fit within the extension of the casing aforesaid, said extension having means for permitting communication between said coil and a pipe connection, means for detachably securing said extension of said coil to said casing, an extension at the opposite end of said coil, and means for detachably securing said extension to the extension of the removable head. 85
  4. In a water heater, a tubular heating coil, and separate coupling elements having elbow portions secured to the ends of said coil and being provided with axial nipple extensions, and means on said coupling elements for detachably securing said coupling extensions of the coil to the opposite end portions of an encasing shell. 90
  5. In a water heater of the character described, a casing having a removable head, an internal extension on said removable head, a tubular coil within said casing, and a fitting on one end of said coil including an angular extension, an elbow portion, a collar, and a threaded coupling nut for detachably coupling the said fitting on the extension of the removable head, substantially as described. 95
  6. In a water heater of the character described, a casing having a bore in the end thereof and a removable head, a tubular coil within said casing, said coil being detachably connected at one end to the removable head and having at its other end a fitting including an angular extension, an elbow portion, a collar to seat the fitting on said bore, and a nipple extension for insertion through said bore. 100
  7. In a coupling element for a coil, a fitting including an angular extension, an elbow portion, a collar, and a threaded coupling nut on said fitting. 105
